UNITED STATES PATENT OFFICE.

WILHELM PAPE, OF BERLIN, GERMANY, ASSIGNOR TO BERGMANN-ELEKTRICITÄTS-WERKE, AKTIENGESELLSCHAFT, OF BERLIN, GERMANY, A CORPORATION.

STEAM TURBINE.

Application filed February 10, 1925, Serial No. 8,251, and in Germany February 8, 1924.

This invention relates to steam-turbines with a plurality of stages and consists essentially in improvements for compensating the axial thrusts of the several turbine sections.

It is old to compensate the axial thrust in reaction steam turbines by connecting two reaction drums so as to have the thrust exerted by the one drum counteract the thrust of the other. This arrangement has the disadvantage, that with the existing steam turbine models one is bound to a definite subdivision of the reaction stages. If the same model is used for a new construction, for instance for a greater gradient of pressure, a complete compensation of the axial thrusts can only be obtained when the pressure between the two drums is essentially increased, since the diameter of the blades and the number of the stages is given for each drum. In this case the drum which is inserted behind the other will have to work with a much greater heat gradient for the same number of stages and with the same diameter, which will reduce the efficiency of the turbine.

In order to avoid this drawback, according to my invention the plural stage steam turbine is constructed with at least two turbine sections, through which the steam passes in opposite direction, said sections containing stages of impulse and reaction. The impulse stages may thereby be inserted before or after the reaction stages. Moreover, the impulse stages may be replaced by stages, in which the blades of the runner are under a smaller reaction than the reaction stages themselves, that is, the impulse stages provided in the individual turbine sections, may, if desired, operate with slight excess pressure as desired.

In this manner there is obtained a much greater liberty in designing the turbine. It will thus be possible to change the differences of pressure of each reaction part of the turbine entirely as desired, by lengthening the reaction part of the respective turbine section, at the same time shortening the even pressure part, or vice versa by shortening the reaction part and lengthening the impulse part appertaining thereto.

In the example shown in Fig. 1 the two

turbine sections in question are mounted in separate casings *a* and *b*. The casing *a* contains impulse stages *c* and reaction stages *d* and the casing *b* contains also impulse stages *e* and reaction stages *f*. The steam passes through both casings in opposite direction. If, for instance, a new construction shall be designed using the same casings *a* and *b*, and if the axial thrust shall be increased in the casing *b*, the reaction part *f* will be lengthened and therefore constructed with a greater number of stages and the impulse part shortened and therefore constructed with a smaller number of stages.

Fig. 2 shows an arrangement which is especially of advantage for turbines having a large out-put. According to my invention there is added to the two casings *a* and *b* a third casing *g*, which contains three reaction parts *h*, *i* and *k*, which are so arranged that the steam streams parallelly through them, and also in opposite directions. The resultant axial shove of the parts *h*, *i*, *k*, is thereby entirely or partly neutralized by the resultant shove of turbine parts *a* and *b*.

It will of course not be required that the reaction part be constructed as a drum, as shown in Figs. 1 and 2 of the drawing.

I claim:

1. A graded steam-turbine, comprising a plurality of turbine units which are positioned within separate casings, the last of these units containing a number of reaction turbine parts through all of which steam can stream partly in parallel and partly in opposite directions, whereby the resultant axial shove of said last unit counteracts the resultant axial shove of the preceding units.

2. A multiple stage turbine consisting of two turbine sections with counteracting axial thrusts, wherein the turbine sections have both impulse and reaction stages and are mounted in separate housings, as well as a third turbine section with three reaction turbines in a separate housing, two of which are transversed with steam in opposite directions, while the axial thrust of the third reaction turbine counteracts the axial pressure of the two first turbines.

In testimony whereof I have affixed my signature.

WILHELM PAPE.
